PNEUMATIC PUMP

Filed April 24, 1920

2 Sheets-Sheet 2

Fig. 5.

UNITED STATES PATENT OFFICE.

ERASMIUS W. BECK, OF GRIFFIN, GEORGIA.

PNEUMATIC PUMP.

Application filed April 24, 1920. Serial No. 376,248.

To all whom it may concern:

Be it known that I, ERASMIUS W. BECK, a citizen of the United States of America, residing at Griffin, in the county of Spalding and State of Georgia, have invented new and useful Improvements in Pneumatic Pumps, of which the following is a specification.

The object of the invention is to provide an improved construction of pneumatic pump of the type wherein the variations in pressure of air supplied by a suitable condenser or compressor or like source of energy may be relied upon solely to secure the alternate filling and emptying of the reservoir to effect the elevation of the water from the depressed level such as the bottom of a well, to any desired altitude, or in other words, of the type shown in my previous application filed November 13, 1919, and the particular object in view in this connection is to provide for a more effective operation of the controlling agencies or elements by which the fluid pressure in the reservoir is regulated, or is alternately increased or reduced to respectively admit and expel the water or other liquid supplied to the reservoir from the exterior, and with these objects in view, the invention consists in the construction and combination of parts, of which a preferred embodiment is shown in the accompanying drawings, wherein:—

Figure 1 is a vertical sectional view of the apparatus with the parts arranged in the positions which they occupy when the reservoir or casing having been charged with water or other liquid, is about to be expelled by the fluid pressure admitted from the compressor.

Figure 2 is a sectional view of the upper portion of the apparatus on a plane at right angles to that of Figure 1, as indicated by the line 2—2 of said figure.

Figures 3 and 4 are detail views respectively of the guide and operating tubes which serve to direct the movements of the floats.

Figures 5, 6, 7 and 8 are respectively transverse sectional views on the planes indicated by the lines 5—5, 6—6, 7—7 and 8—8 of Figure 1.

The apparatus consists essentially of a submersible reservoir 10 having, for example, a cylindrical wall terminally seated in upper and lower heads 11 and 12 and held

in place by exterior tie rods 13 or the equivalent thereof, a liquid discharge pipe or conductor 14 connecting with a cored passage 15 in the upper head of the reservoir and provided with a check valve 16 to prevent back-flow into the reservoir, an exhaust pipe 17 also communicating with the top of the reservoir through the upper head and adapted to permit the escape of air or fluid pressure during the inflow of the liquid to charge the reservoir, a pressure pipe 18 adapted for connection with the compressor or other source of pressure (not shown) for the purpose of expelling the liquid contents of the reservoir, a valve mechanism for controlling the pressure and exhaust pipes to the end that they may be alternately opened during the filling or exhausting of the reservoir, liquid conductors 19 extending from points near the bottom of the reservoir and communicating with a cored passage 15 to convey the water or other liquid to the discharge pipe 14, and a valved inlet port 20 communicating with the reservoir at its bottom to prevent the influx of water or other liquid when the fluid pressure within the reservoir is relieved.

The inlet valve 21 may be of any preferred construction suitable to be seated for example by gravity and located in a cage 22 with a suitable guide opening 23 to insure the proper seating thereon when the fluid pressure is introduced into the reservoir to avoid waste by leakage and the port 20 preferably communicates with a cored inlet passage 24 formed in the base or lower head of the reservoir to permit the lateral inflow of water from the space within which the reservoir is located.

Arranged in an upright position and preferably concentrically in the reservoir is a guide tube 25 upon which is mounted for sliding movement a valve operating float 26 limited in its downward movement by a stop 27 and arranged in operative relation with said float is a latch or retainer 28 consisting of toggle arms pivotally mounted as at 29 to the guide tube 25 and connected with the upper end of a valve operating member 30, which may be of tubular construction as indicated and attached at its lower end to a buoyant member 31, such as a hollow air-tight chamber arranged near the bottom of the reservoir, and hence exposed to the buoyant effect of the

liquid contents of the reservoir and practically at all times during the operation of the pump, to the end that there may be practically a constant upward tendency of said 5 buoyant member serving to maintain an upward impulse in the operating member 30 which, as illustrated operates in the bore of the guide tube 25.

Arranged in the path of said operating 10 member is a trip lever 32, fulcrumed as at 33 and having a trip latch 34 arranged in operative relation with a ball valve 35 which controls the port 36 by which communication is established between the pressure supply tube 18 and the interior of the reservoir, said valve being gravity closing in form, and arranged to the end that it will close with the pressure from the supply. The upward movement of the operating member 30 15 serving to raise the free end of the trip lever 32 will shove said valve from its seat to permit of the introduction of pressure into the reservoir to expel the charge of water which previously has been admitted thereto.

20 Also arranged in operative relation with the member 30 is a discharge valve 36', arranged to open inwardly or toward the reservoir to control communication between the reservoir and the discharge pipe 17, said 25 valve in the construction illustrated being of the coned or tapered type having a guide stem 37 and having operating stem 38 with which is slidably connected, a thimble 39 on the upper end of the operating member 30, 30 a head 40 on the lower end of said stem serving to limit the relative downward movement of the operating member and a cushion spring 41 coiled upon the said stem serving to effect the yielding seating of the 35 valve due to an upward movement of said operating member.

The toggle retainer 28 is arranged to operate through slots 42 and 43 formed in registration in the guide tube 25 and operating 45 member 30, so that when the buoyant member 31 is elevated as indicated in Figure 1, the jointed elements of the retainer project laterally beyond the surface of the guide tube, and the retainer is arranged in the 50 zone of movement of the float 26 so that whereas when the float is in its elevated position, indicated in Figure 1 to which it is moved by the liquid contents of the reservoir when the latter is fully charged, it is located 55 above the retainer and the buoyant member raises the latter to permit of its spreading movement. The location on the float in its depressed position, in which it rests upon the stop 27, serves to prevent the expansion 60 or spreading, and thus through the retainer maintains the buoyant member 31 in its depressed position and hence through the operating member 30 enables said buoyancy member to hold the exhaust valve 36 unseated, and at the same time prevents the con-

tact of the operating member with the trip lever and allows the pressure valve 35 to remain seated.

Thus with the parts in the position indicated in Figure 1 of the drawing, wherein the float is elevated to release the retainer 28 and hence with the buoyant member 31 in its elevated position to seat the said valve through direct action of the operating member 30 upon the exhaust valve and also upon the trip lever 32, to unseat the pressure valve, the apparatus is in position to permit of the introduction of fluid pressure to the reservoir to cause the pneumatic expulsion of the charge of liquid therein through the conductors 19, the cored passage 15 and the exhaust pipe 14. Obviously the float 26 tends to follow the parallel movement of the surface of the water in the reservoir, but is prevented from dropping by reason of the expansion of the retainer 28 until the level of the water in the reservoir is depressed to such a point as to permit of the downward movement of the buoyant member 31. When this occurs, the retainer is collapsed so as to relieve the float 26 which drops into contact with the stop 27 and hence in the plane of the retainer which it continues to embrace and lock in a collapsed condition until again raised by the action of the water in the filling operation. The depression of the buoyant member 31 lowers the pressure valve 35 and permits it to seat so as to cut off the in-flow of compressed air and also unseats the exhaust valve so that the water or other liquid in which the reservoir is submerged, acted upon by gravity or atmospheric pressure unseats the inlet valve 21 and flows into the reservoir discharging the air contained therein through the exhaust pipe 17 until the level of the water, again reaching the float 26 and raising the latter serves to operate the retaining device and hence permit the upward movement of the buoyant member 31 to again reverse the positions of the pressure and exhaust valves and by cutting off the escape of air from the interior of the reservoir and admitting the compressed air from the feed pipe 18 providing for the pneumatic expulsion of the liquid charge which has been admitted.

It will be noted the buoyant member is of relatively large capacity so that the effect of the water or other liquid thereon tending to raise the same will be opposed by the retaining device until such time as the level of the water in the reservoir rises to a point sufficient to elevate the float 26 and ensure the prompt reversal of the positions of the pressure and exhaust valves in said releasing of the retainer, so that an effective re-adjustment of the valves is assured and the possibility of a leakage is avoided. In the opposite or reverse re-adjustment of the valves the weight of the buoyant member is suffi-

cient, particularly in the reduction of internal pressure in the reservoir and the positive pressure in the supply pipe 18 to ensure an effective movement of the pressure and exhaust valves.

The invention having been described, what is claimed as new and useful is:—

1. A pneumatic pump having a submerged reservoir provided near its bottom with an inlet and outlet for liquid, the former being controlled by an inwardly opening valve, pressure inlet and relief valves controlling pressure inlet and exhaust ports in communication with the reservoir near its top, said inlet and relief valves being respectively mounted for inward seating and unseating movements, a trip mechanism arranged in operative relation with the inlet valve, an operating member mounted for reciprocatory movement and having an element of said trip mechanism arranged in the path of upward movement thereof, a cushioned connection between said operating member and the relief valve, a buoyant member for said operating member, a retainer for securing the operating member in its depressed position, and a float movable into and out of the plane of the retainer for alternately locking and releasing the same.

2. A pneumatic pump having a submerged reservoir provided near its bottom with an inlet and outlet of which the former is valved, pressure inlet and relief valves controlling pressure inlet and exhaust ports in communication with the interior of the reservoir at its top, the pressure inlet valve being of the ball type and arranged to seat inwardly with relation to the reservoir, and the relief valve being arranged to unseat inwardly with relation to the reservoir, a guide tube, a buoyant member having a tubular operating member mounted for sliding movement in said guide tube and having a cushioned connection with said relief valve, an inlet valve trip lever terminally arranged in the path of said operating member and having a trip pin for displacing said inlet valve, a retainer connected with said op-

erating member consisting of toggle arms 50 expansible through slots in the guide tube, and a float mounted for sliding movement upon the guide tube into and out of the zone of said retainer for alternately locking and releasing the latter, the downward movement 55 of said float being limited to a position in the zone of the retainer.

3. A pneumatic pump having a submerged reservoir provided near its bottom with an inlet and outlet for liquid the former being 60 controlled by inwardly opening valves, pressure inlet and relief valves controlling pressure inlet and exhaust ports in communication with the reservoir near its top, a buoyant member located within the reservoir for 65 effecting the reversal in positions of the pressure inlet and relief valves and having a limited movement in the zone confined to the bottom of the reservoir, a retainer actuated by said buoyant member, and a float 70 having its zone of operation confined to the top of the reservoir and engageable with said retainer on recession of the contents of the reservoir to lock the float in depressed position. 75

4. A pneumatic pump having a submerged reservoir provided near its bottom with an inlet and outlet for liquid, the former being controlled by an inwardly opening valve, pressure inlet and relief valves controlling 80 pressure inlet and exhaust ports in communication with the reservoir near its top, said inlet and relief valves being respectively mounted for inward seating and unseating movements, a trip mechanism arranged in 85 operative relation with the inlet valve, an operating member mounted for reciprocatory movement and having an element of said trip mechanism arranged in the path of upward movement thereof, a buoyant 90 member for said operating member, a retainer for securing the operating member in its depressed position, and a float movable into and out of the plane of the retainer for alternately locking and releasing the same. 95

In testimony whereof he affixes his signature.

ERASMUS W. BECK.
